DISPLAY RACK

Alexander Sjodin, Rush City, and Charles J. Olund and Robert J. Moody, Cambridge, Minn.

Application June 18, 1931, Serial No. 545,220

7 Claims. (Cl. 211—115)

This invention relates to new and useful improvements in display racks and more particularly to such racks adapted to be movably suspended from an overhead support.

5 An object of the invention is to provide a movable display rack adapted for use in stores and other places, to display merchandise to be vended, said rack having means for receiving standard cooky boxes whereby the cookies therein may be displayed in the boxes in which they are received from the factory, as is now common practice, said boxes usually being provided with glazed closures or doors, and said boxes being arranged in spaced relation thereon, and at a slight angle whereby the cookies in the boxes may readily be seen.

10 A further object is to provide a display rack adapted to be suspended by means of a flexible element such as a chain, whereby the display rack is adapted for rotary and swinging movements thereby causing it to attract the attention of patrons entering the store or place where the display rack is employed.

15 A further object is to provide a display rack of the character described, particularly adapted for use in stores, whereon articles and merchandise may be displayed in a pleasing and attractive manner with a resultant increase in the number of sales, the construction of the rack and its supporting means being such as to cause it to move almost continuously in a rotary or swinging fashion, whereby it will quickly attract the attention of a prospective purchaser entering the store.

20 Other objects of the invention reside in the construction of the display rack whereby it may readily be taken apart and packed into a comparatively small bundle for shipment; in the construction of the main supporting structure which consists of a plurality of upright angle plates secured together in spaced relation and having means therebetween for supporting articles or containers to be displayed; in the means for securing together said angle plates whereby the display rack may be quickly taken apart and set up again when necessary; to provide a display rack shaped to simulate a pyramid and having its walls composed of a plurality of plates detachably secured together, and each provided with a plurality of openings adapted to receive containers or articles to be displayed; in the provision of a display rack comprising a plurality of compartments each provided with a glazed door and having a plurality of uprights detachably secured thereto, the upper ends of which are secured together and provided with means whereby the rack may be suspended from an overhead support; in the provision of a plurality of shelves on said uprights; and, in the provision of a conically shaped display rack pro-

vided with a plurality of annular shelves adapted to receive articles and goods for display purposes, and provided at its upper portion with means whereby it may be suspended from an overhead support.

25 Other objects of the invention will appear from the following description and accompanying drawings and will be pointed out in the annexed claims.

30 In the accompanying drawings, there has been disclosed a structure designed to carry out the various objects of the invention, but it is to be understood that the invention is not confined to the exact features shown as various changes may be made within the scope of the claims which follow.

35 In the drawings:

Figure 1 is an elevational view partially in section, showing one form of the invention;

Figure 2 is a plan view of Figure 1, partially in section to show the arrangement of the angle plates forming the supporting structure of the rack;

Figure 3 is a view showing one of the triangularly shaped shelves removed from the structure;

Figure 4 is a perspective view showing a display rack of pyramidal shape;

Figure 5 is a cross sectional view illustrating the interior construction of the rack shown in Figure 4;

Figure 6 is a detail sectional view on the line 6—6 of Figure 5;

Figure 7 is a detail sectional view on the line 7—7 of Figure 4;

Figure 8 is a sectional elevation showing another form of display rack having a plurality of radially disposed compartments provided at the lower portion thereof and the upper portion thereof comprising inclined uprights adapted to support suitable shelves;

Figure 9 is a sectional plan view on the line 9—9 of Figure 8;

Figure 10 is a detail sectional view on the line 10—10 of Figure 8;

Figure 11 is a perspective view showing a display rack of conical shape;

Figure 12 is a detail sectional view on the line 12—12 of Figure 11;

Figure 13 is a detail sectional view showing the connection between the annular shelves and the cone-shaped body of the rack; and

Figure 14 is a detail sectional view through the upper portion of the rack shown in Figure 11, illustrating the means provided whereby the rack may be suspended from an overhead support.

The display rack featured in Figures 1, 2, and 3 is shown comprising a plurality of angle plates 2, each provided with upright walls 3, as best shown in Figure 2. The angle plates 2 are shown

65

70

disposed in right angular formation and are spaced apart by suitable supporting members or plates 4, arranged at an incline, as shown in Figure 1. Each supporting plate 4 preferably

6 has its opposite edges bent upwardly to provide flanges 5, whereby said plates may be secured to the adjacent walls 3 of the angle plates 2. An upturned flange 6 is provided at the inner end of each supporting plate 4 to provide stops 10 for the cartons or boxes 7, shown in Figure 1. These cartons or boxes may be of the type usually employed in grocery stores for displaying cookies and such articles, each being provided with a glazed door or window 8, as shown in Figure 2.

15 The supporting shelves 4 are preferably arranged at an angle, as shown in Figure 1, so as to tilt the boxes 7 to positions whereby the articles or goods contained therein may readily be viewed by persons passing by the display rack.

20 Suitable triangularly shaped shelves 9 are secured in position in the outwardly facing corners of the angle plates 2, as best illustrated at the left hand side of Figure 2. Each shelf 9 is here shown provided with depending flanges 11 having

25 suitable apertures 12 therein adapted to receive bolts or screws which pass through similar apertures provided in the walls 3—3 of each corner plate. The vertical edges of the walls 3—3 of each angle plate 2 are notched or shaped like

30 saw teeth so as to conform to the angular position of the boxes 7 upon the supports 4, and whereby a neater appearance is presented.

Suitable plates 14 are shown secured to the upper portions of the angle plates 2 and each 35 is provided with an upright inclined portion 15 which portions are adapted to be secured together at the corners, as illustrated in Figures 1 and 2. A small plate 16 may be secured to the upper portion of the structure to provide 40 means for supporting a suitable hook or eye-bolt 17, adapted to be engaged with a suitable chain 18 whereby the rack may be suspended from a ceiling or overhead support.

The shelves 9 secured in the corners of the 45 angle plates 2, as shown at the right hand side of Figure 1 and at the left hand side of Figure 2, are adapted to support such articles for example, as canned goods, indicated at 19 and 21 in Figure 1. The angle plates 2, supporting plates 50 4, shelves 9, and top plates 14, may all be secured together by suitable bolts whereby the entire apparatus may be quickly taken apart, if necessary. A suitable finishing plate 22 is disposed over the top plates 14 to provide a more finished appearance to the rack. Articles to be displayed may also be supported upon the top plate 22.

The display rack shown in Figures 4 to 7, inclusive, comprises oppositely disposed triangularly shaped plates 23—23 and similarly shaped plates 24—24. The plates 23—23 are here shown provided with inwardly turned marginal flanges 25, against which the marginal edge portions 24—24 may be seated and secured by suitable stove bolts 26.

The plates 23—23 are each provided with a plurality of openings formed by inwardly turning portions of the metal thereof to provide inclined bottoms 27 adapted to support containers or cartons 28 such, for example, as cooky boxes. These boxes are provided with the usual glazed doors 29 whereby the articles or goods contained therein may be viewed by persons passing the display rack.

75 The plates 24—24 are shown provided with

three openings similar to those shown in the plates 23, adapted to receive similar cooky boxes 28. These plates, in addition, are shown provided with a plurality of pigeon holes 30, 31, and 32, having their bottoms substantially horizontally disposed so that small articles or canned goods may be supported thereon for display purposes. These pigeon holes are also provided with upright walls whereby small articles displayed therein cannot accidentally drop into the interior of the display rack. (See Figure 7).

80 The means for supporting the display rack from an overhead support consists of a plate 33 fitting beneath the inwardly turned top flanges 34 of the plates 23 and 24 as best shown in Figure 5. A suitable hook or eye-bolt 35 has its upper end received in an aperture provided in the plate 33, and extends downwardly therefrom and has a sleeve 36 mounted thereon, which sleeve is shown provided with suitable hooks 37 and 38 adapted to receive supporting rods or wires 39 and 41, respectively, which are secured to the inclined bottoms 27 which support the boxes 28. A nut 42 is shown received in threaded engagement with the lower end of the eye-bolt 100 35 so as to securely clamp the upper end of the sleeve against a washer 43, seated against the bottom of the plate 33, and whereby all of the parts will be rigidly secured together as a unit. The hook 35 may be engaged with a suitable 105 supporting chain 18, as shown and described with reference to Figure 1.

90 The display rack illustrated in Figures 8 to 10, comprises a plurality of compartments 44, defined by upper and lower walls or plates 45 and 46, respectively, and a plurality of radially disposed partitions 47, preferably constructed as shown in Figure 9. Each compartment is provided with an outer wall 48 having openings 49 therein provided with suitable glazed doors or 110 closures 51, whereby access may be had to the compartments, and also whereby the material or goods contained in said compartments may be viewed from the exterior of the rack.

95 The lower portion of the display rack, comprising the compartments 44, is supported by means of a plurality of uprights 52 having their lower terminals spaced apart and passing through suitable apertures provided in the top wall 45. Suitable pins 53 are secured in the lower ends of 120 the uprights 52 within the compartments 44 to prevent them from accidentally becoming disengaged therefrom. The uprights preferably taper inwardly and have their upper end portions 54 beveled and fitted together, as shown in 125 Figures 8 and 10. A cap 55 fits over the ends of the uprights 52 and has an aperture in the upper wall thereof adapted to receive an eye-bolt 56 which passes downwardly between the ends of the uprights 52 and has a suitable wedge 57 provided at the lower end thereof. A nut 58 is received in threaded engagement with the lower end of the eye-bolt 56, whereby the wedge may be forced upwardly, causing the upper ends of the uprights to expand against the walls of 130 the cap 55, whereby they will be firmly secured in position within the cap.

135 A plurality of suitable shelves 59 and 61 are detachably supported upon the uprights 52 in spaced relation. These shelves cooperate with the top wall 45 of the lower portion of the structure to provide shelves for receiving and supporting articles or goods to be displayed, as indicated by the dotted lines 62 in Figure 8. The display rack may be supported in a manner sim- 140 145 150

ilar to that shown and described with reference to Figures 1 and 4.

The display rack illustrated in Figures 11 to 14, inclusive, comprises a plurality of segmental plates 63 provided with inwardly turned marginal flanges 64 adapted to be abuttingly engaged and secured together by suitable stove bolts 65, as best shown in Figure 12. When these plates are thus secured together, they provide a conically shaped body, as illustrated in Figure 11.

A plurality of annular members 66, 67, and 68 are demountably supported upon the conically shaped body of the structure adapted to support articles which are to be displayed. Each annular shelf is provided with a marginal flange 69 adapted to be seated against the surfaces of the plates 63, as clearly illustrated in Figure 13. A small circular plate 71 is fitted into the upper end of the cone-shaped body and has an eye-bolt 72, whereby the rack may be supported from a chain 18 in a manner similar to that shown and described with reference to the other figures.

The display rack featured in this invention has been found very useful in such places as grocery stores and other places where small articles are vended. The articles to be displayed are placed upon the display rack, as hereinbefore described, so that they may readily be viewed by persons entering the store. When a customer is looking over the goods on display on the rack, he need not walk around the rack to see the various articles displayed thereon, but may view them by simply rotating the rack, which greatly adds to the attractiveness of the apparatus. It is also to be understood that when once a rotary or swinging movement has been imparted to the display rack, it will continue so to move for a long period of time, thereby attracting the attention of prospective purchasers when entering the store. The invention also provides a display rack which may be quickly taken apart and stored away in a comparatively small space, when necessary. This feature is especially important when shipping the display racks from one place to another.

We claim as our invention:

1. A display rack comprising a plurality of angle plates arranged in spaced relation and having their outer edges stepped, inclined supporting plates interposed between and secured to said angle plates, means secured to the upper portions of said angle plates whereby the rack may be suspended from a suitable overhead support, and stops at the inner ends of said supporting plates whereby a conventional cooky box may be supported on each of said plates, the inclination of said plates causing said boxes to be supported in an angular position whereby the contents thereof may readily be viewed by prospective customers passing thereby.

2. A display rack comprising a plurality of upright angle plates arranged in spaced relation, means interposed between and securing together said angle plates and providing supports for articles or containers to be displayed, a member secured to the upper portions of said angle plates and having a horizontal portion provided with an angular opening axially aligned with the rack, and a plate element having a portion fitting in said opening and provided with means whereby the rack may be suspended from a suitable overhead support.

3. A display rack comprising a plurality of angle plates arranged in spaced relation and facing outwardly, inclined supporting plates interposed between and secured to said angle plates and providing supports for articles or containers to be displayed, said supporting plates having upturned flanges at their inner edges providing stops for food containers supported thereon, a plurality of shelves secured to said angle plates in the corners thereof whereon small articles may be displayed, and a member secured to the upper portions of said angle plates and having means whereby the rack may be suspended from an overhead support.

4. A display rack comprising a plurality of angle plates arranged in spaced relation and facing outwardly, flanged supporting plates interposed between and detachably securing together said angle plates and providing supports for articles or containers to be displayed, a top member secured to the top portions of said angle plates and having an opening therein, and a plate element fitting in said opening and provided with means whereby the rack may be freely suspended from a suitable overhead support.

5. A display rack comprising a plurality of upright angle plates arranged in spaced relation, flanged plates interposed between and detachably securing together said angle plates and providing supports for articles or containers to be displayed, a top member secured to the upper portions of said angle plates and comprising an upright portion, means secured to said upright portion whereby the rack may be suspended from a suitable overhead support, and a plate horizontally disposed on said top member and having an aperture adapted to receive said upright portion, said plate functioning as a shelf for supporting additional articles to be displayed.

6. A display rack comprising a plurality of angle plates arranged in spaced relation and facing outwardly, supporting plates interposed between and detachably securing together said angle plates and providing supports for articles or containers to be displayed, said supporting plates being arranged at an incline whereby articles supported thereon will be tilted, a plurality of horizontally disposed shelves demountably secured to said angle plates at the corners of the rack whereon small articles may be displayed, and a top member secured to the upper portions of said angle plates and provided with means whereby the rack may be suspended from an overhead support.

7. A display rack comprising a plurality of plates of angular cross-section arranged in spaced relation and facing outwardly, supporting plates interposed between and secured to said angle plates and providing supports for articles or containers to be displayed, a plurality of triangularly shaped shelves secured to said angle plates at the corners of the rack and disposed in vertically spaced relation and each having an annular depending flange, and plates secured to the upper portions of said angle plates and provided with means whereby the rack may be suspended from an overhead support.
